J. BODNAR

CAN OPENER

Filed May 21, 1920

FIG. 1.

FIG. 2.

FIG. 3.

INVENTOR

JOHN BODNAR

Joseph J. Bodnar

ATTORNEY

UNITED STATES PATENT OFFICE.

JOHN BODNAR, OF SPRINGFIELD, MASSACHUSETTS.

CAN OPENER.

Application filed May 21, 1920. Serial No. 383,238.

To all whom it may concern:

Be it known that JOHN BODNAR, a citizen of the United States of America, residing at Springfield, in the county of Hampden and State of Massachusetts, has invented certain new and useful Improvements in Can Openers, of which the following is a specification.

This invention relates to improvements in can openers and its leading object is to provide a simple can opener for shoe polish and similar cans which will positively open a can by a simple thumb movement which can be effected by the use of one hand and consists of a yoke like lever pivoted near its terminal portions to the can cover and provided with a thumb engageable projection or lug and means for engaging an external bead on the can bottom, whereby the cover and the bottom will be separated from each other when the lug carrying portion of the lever or yoke is forced outwardly of the can top.

With the above and other objects in view this invention relates to certain new and useful constructions, combinations and arrangements of parts, clearly described in the following specification and fully illustrated in the accompanying drawings, in which:

Figure 1 is a side elevation.

Figure 2 is a plan view.

Figure 3 is a detail sectional view taken on line 3 of Figure 1.

Referring to the accompanying drawings 35 5 designates the can bottom which is provided with an external bead 6 of considerable depth and which provides a seat for the flange 7 of the can top 8.

The flange 7 is formed with an outwardly 40 directed ear 9 located on each side thereof and in diametric opposition to each other.

A yoke like lever 10 is pivotally connected by means of the rivets or like 11 to the ears 9, this lever being of U shaped formation 45 and snugly fitting against the outer face of

the flange 7 of the can top 8. The lever 10 is formed with a thumb engageable external lug 12 and the pivots 11 are located inwardly of the ends of the lever so as to provide short terminal arms 13 and 14 which are 50 adapted to be moved against the external bead of the can bottom when the finger hold or lug 12 is moved by finger or thumb pressure upwardly. When the yoke is thus tilted the can bottom will be separated from the 55 can top and ready access obtained to the contents of the can.

In order to reinforce the lever 10 the same is provided with a bead 10^a and the terminal portions of the lever are provided 60 with inset bead engaging flanges 15, whereby the short arms 13 and 14 will be maintained in correct working engagement with the external bead of the can.

The improved opener can be constructed 65 of any material and when applied to a can in no way interferes with the economical manufacture and easy use of the can or its contents.

Having described my invention, I claim: 70

The combination with a can, including a bottom and a cover, and the bottom having an external circular flange located below its upper edge and said upper edge being insertable in the cover, said cover being provided with upwardly turned integral ears, located in opposite sides thereof, a U-shaped lever having terminal portions pivotally connected with said ears and projecting beyond said pivotal connections, the 75 central portion of the lever having an outset finger hold, the lever normally resting in bodily contact with the flange, being normally protected against accidental displacement by said flange, the lever having a medial reinforcing flange coextensive with its 80 length.

Signed by me at Springfield, Massachusetts.

JOHN BODNAR.
